UNITED STATES PATENT OFFICE.

FREDERICK G. WISELOGEL, OF INDIANAPOLIS, INDIANA, ASSIGNOR TO
UNITED STATES CONSTRUCTION AND UTILIZATION COMPANY, OF
ROCHESTER, NEW YORK, A CORPORATION OF NEW YORK.

EVAPORATOR AND EXTRACTOR FOR GARBAGE REDUCTION.

No. 857,372.

Specification of Letters Patent.

Patented June 18, 1907.

Application filed October 9, 1906. Serial No. 338,174.

To all whom it may concern:

Be it known that I, FREDERICK G. WISELOGEL, a citizen of the United States, residing at Indianapolis, in the county of Marion 5 and State of Indiana, have invented certain new and useful Improvements in Evaporators and Extractors for Garbage Reduction, of which the following is a specification.

The object of my invention is to produce an apparatus for receiving garbage and extracting therefrom the fats and oils, at the same time drying the material.

The accompanying drawings illustrate my invention:

- 15 Figure 1 is a longitudinal vertical section; Fig. 2 an elevation; Fig. 3 a transverse section, and Fig. 4 a transverse sectional detail of the removable filter diaphragm.
- 20 In the drawings, 10 indicates a cylindrical or substantially cylindrical structure closed at its ends by heads 11 and 12, each of said heads having a central bearing in which is journaled a shaft 13 provided with stirring blades 14 which traverse the chamber or main 25 body closely adjacent the bottom. The main body 10 is preferably formed of a pair of mating bottom castings 10'-10", and a single saddle casting 10''. The two castings 10' are so formed at their adjacent edges as 30 to form a longitudinal channel 15 which is depressed below the main line of the walls of the cylinder and formed in each vertical edge of the channel is a longitudinal groove 16 adapted to receive the opposite edges of a 35 perforated plate 17 which extends the entire length of the chamber. Plate 17 carries above it a perforated plate 18, preferably having finer perforations and being spaced from plate 17 by suitable thimbles 19 and 40 bolts 20. Laid between plates 17 and 18 is a filter mat 21, formed conveniently of burlap or other similar fabric. The upper plate 18 of the filter lies substantially in line with, and as a continuation of, the inner faces of the 45 castings 10''. In order to facilitate the removal and replacement of the filter structure I provide the head 11 with a door 25 which may be swung so as to open the entire space at the end of channel 15 and thus permit 50 plate 17, with its attached parts, to be withdrawn longitudinally from the structure. Castings 10' and 10'' are thicker at their adjacent edges than at intermediate points and a sheet jacket 26 is bridged over the space 55 between the thickened edges, thus forming at

the bottom of the cylinder a pair of steam jackets 27-27 and at the top a water jacket 28, steam pipes 29 leading into jackets 27 and suitable water circulating pipes 30 leading into and out of the water jacket 28. 60 Suitable pipes 35 give access to the interior of the cylinder at the top thereof and a pipe 36 leads from the channel 15.

In operation the garbage is introduced through pipes 35 and a sufficient quantity of 65 alcohol or benzin introduced. Pipes 35 are then closed and the chamber is heated by steam within jackets 27. Shaft 13 is then rotated and the garbage thoroughly heated, the gases passing off through an outlet 40 70 while the grease and oils settle to the bottom chamber and pass through the filter mat 21 and perforated plates 17 and 18 through channel 15, from whence they may flow through pipe 36. The outflow of gases may 75 be retarded by a suitable valve (not shown) in a continuation of the pipe 40. As the cooking proceeds the volatile alcohol or benzin rises to the top of the chamber where, 80 coming in contact with the cooling saddle, it is condensed and returned to the mass. When the material has been thoroughly dried and all the oils and grease extracted the dried material may be discharged through the opening closed by door 25 by rotation of 85 the stirrer. When it is desired to renew the filter mat the filter structure may be readily withdrawn longitudinally through the same opening and a new mat placed therein.

I claim as my invention:

In an extractor and evaporator, the combination with a receiving chamber having a longitudinal slot in its bottom and an opening in its head at the end of said slot, a closure for said opening, and a filter structure supported in said channel and longitudinally withdrawable therefrom through the opening in the head, a heating jacket embracing the lower side of the receiving chamber and a cooling saddle embracing the upper side of said chamber.

In witness whereof, I, have hereunto set my hand and seal at Indianapolis, Indiana, this 3rd day of October, A. D. one thousand nine hundred and six.

FREDERICK G. WISELOGEL. [L. S.]
